STEERING APPARATUS

Herbert C. Bowen, Detroit, Mich., assignor to Hydraulic Brake Company, Detroit, Mich., a corporation of California

Application May 11, 1933, Serial No. 670,615

6 Claims. (Cl. 60—54.5)

This invention relates to steering apparatus, and more particularly to hydraulic means for operating a rudder.

Broadly the invention comprehends hydraulic apparatus for operating a rudder such as is used in steering a motor boat or aircraft, including hydraulically actuated means for operating the rudder and a remote hydraulic apparatus for controlling the hydraulically actuated means.

10 In the illustrated embodiment of the invention hydraulically actuated means associated with a rudder is arranged for operation by a manually operated hydraulic control means to effectively shift the rudder without loss of motion.

15 An object of the invention is to provide a steering means including hydraulic apparatus for shifting a rudder of a motor boat or aircraft without noise and vibrations.

Another object of the invention is to provide 20 hydraulically actuated means for shifting a rudder, and hydraulic operating mechanism so arranged and connected thereto that the rudder may be moved from one position to another smoothly, quietly, without vibrations, and without imposing excess pressure on the pipe lines or 25 conduits connecting the hydraulically actuated means with the hydraulic operating means.

A further object of the invention is to provide 30 apparatus for actuating a rudder, including a remote hydraulic operating means suitably connected to hydraulic actuating means, and to arrange the component parts of the apparatus so that the structure will be highly efficient in 35 operation, yet of marked simplicity as a whole and in respect to each of the component parts, so that manufacture may be economically facilitated both as regards to parts and their assembly.

Other objects and advantages of the invention 40 will appear from the following description taken in connection with the drawings which form a part of this specification, and in which,—

45 Figure 1 is a back elevation of the fluid pressure actuating mechanism, partly broken away and partly in section.

45 Figure 2 is a longitudinal sectional view of a fluid pressure actuated mechanism.

Figure 3 is a detailed view of a bracket supporting the rudder post and rudder, with parts broken away.

50 Fig. 4 is a schematic view illustrating the fluid pressure actuating mechanism and the fluid pressure actuated mechanism and the fluid pressure delivery pipes connecting these devices; and

55 Fig. 5 is a fragmentary view of the actuating

mechanism in section illustrating the valve mechanism.

Referring to the drawings for more specific details of the invention, 10 represents a casing or housing which may be of any desirable structure. The casing has a drain opening in which is threaded a plug 12 and a cover plate 14 provided with a filling opening adapted to be closed as by a cap 16. The casing is secured to brackets 18 and 20 which may be attached to a suitable support, not shown.

The casing has oppositely disposed openings in which are fitted corresponding sleeves 22 and 24 having flanges bolted or otherwise secured to the casing. The sleeves 22 and 24 support opposed cylinders 26 and 28. The heads of the cylinders have concentric portions 30 and 32 provided with axial passages or ports 34 and 36 communicating with the respective cylinders. The heads of the cylinders also have radial openings 38 and 40 communicating with the passages 34 and 36, respectively, and ports 42 and 44 communicating with the radial openings 38 and 40, respectively. The radial openings 38 and 40 are respectively controlled by valves 46 and 48.

Positioned for reciprocation in the opposed cylinders 26 and 28 is a double end piston 50. The piston is provided with oppositely disposed heads 52 and 54 fitted snugly in the respective cylinders 26 and 28, and the body of the cylinder 30 has a smaller diameter than the diameter of the heads to provide suitable clearance as indicated at 56 and 58.

The piston has a centrally located slot 60 and is axially bored as at 62 and 64, and just back of the respective heads 52 and 54 are ducts or passages 66 and 68 leading from the bores 62 and 64, respectively, to the circumference of the reduced portions of the piston. Positioned on the heads of the piston are leak-proof cups 70 and 72 having openings therin coextensive with the bores 62 and 64. These cups control the passages 66 and 68 and provide for by-passage of fluid from the reservoir to the respective cylinders upon alternate retraction strokes of the piston.

Fitted in the bores 62 and 64 are plungers 74 and 76, held in position by plates or stops 78 and 80 secured to the adjacent ends of the plungers within the slot 60. The plungers have extended portions 82 and 84 which project through the openings in the cups 70 and 72, and suitably secured to the extended portion are collars 86 and 88 and positioned on the extended portion between the collars and the respective cups are 55

coil springs 90 and 92. The springs serve to yieldingly retain the cups in position. The extended portions have conical ends as shown at 94 and 96 which direct the extended portions 82 and 84 into the respective passages 34 and 36 where they retain the valves 46 and 48 in open position so that fluid may be returned to the cylinders 26 and 28.

The casing supports for rotation a shaft 98 which may be moved through an angle by a suitable hand wheel 100 keyed or otherwise secured thereto, and suitably secured on the shaft is an arm 102 having a part 104, preferably semi-spherical, positioned in the slot 60 and adapted to engage the plates or stops on the adjacent ends of the plungers 74 and 76.

A fluid pressure actuated mechanism indicated generally at 106 is associated with a rudder 108 which may be of any preferred type. As shown, the actuating mechanism includes a bracket 110 supporting opposed cylinders 112 and 114. The cylinder 112 has a head 116 provided with an axial port 18 controlled by a check valve 120, and connected with the valve is a pipe line 122 leading to the valve 48 in the head of the cylinder 26 of the actuating mechanism. The head 116 also has a radial bore 124 connected by a pipe line 126 to the port 34 in the head of the cylinder 26. The cylinder 114 has a head 128 provided with an axial bore 130 controlled by a check valve 132 connected by a pipe line 134 to the valve 46 in the head of the cylinder 26. The head 128 on the cylinder 114 also has a radial port 136 connected by a pipe line 138 to the axial bore 36 in the head of the cylinder 26.

A double headed piston 140 is positioned for reciprocation in the cylinders 112 and 114. The heads 142 and 144 of this piston have thereon concentric extensions 146 and 148 and leak-proof cups 150 and 152. Collars 154 and 156 are suitably secured to the extended portions, and positioned on the extended portions between the collars and the cups are coil springs 158 and 160 for retaining the cups in position. The extended portions have reduced portions 162 and 164 adapted to enter the passages 118 and 130, respectively, to trip the valves 120 and 132, respectively depending upon the direction of movement of the piston 140 and the reduced portions 50 are provided with passages 166 and 168, respectively, to permit the passage of fluid.

The rudder 108 is suitably secured to a post 170 journaled on the bracket 110, and the post has suitably secured thereto an arm 172 having a semi-spherical end 174 positioned in slot 176 centrally located in the piston 140.

In operation, assuming that the system is filled with suitable hydraulic fluid or liquid, upon turning the steering wheel 100 to the left the arm 102 is moved through an angle to apply force to the piston 50, causing the piston to move to the right. Movement of the piston to the right displaces fluid from the cylinder 28 through the pipe line 138 to the cylinder 114, causing movement of the piston 140 to the left, resulting in turning the rudder to the right.

During this movement of the piston 50 the valve 48 is opened by the conical portion 96 on the extension 84 of the piston 76 and the valve 120 is closed. As the piston 140 is moved to the left to effectively shift the rudder to the right, the fluid or liquid in the cylinder 112 is displaced through the pipe line 126 to the cylinder 26, and at the end of the stroke the valve 120 is opened

so as to relieve pressure in the pipe line 122 and equalize the pressure in the system.

Upon turning the steering wheel 100 to the right, the arm 102 is moved through an angle to apply force to the piston 50 and cause movement thereof to the left. This movement displaces fluid from the cylinder 26 through the pipe line 126 to the cylinder 112, causing movement of the piston 140 to the right, resulting in turning the rudder to the left.

During this movement of the piston 50 the valve 46 is opened by the conical end 94 on the extension 82 of the plunger 74 and the valve 132 is closed. As the piston 140 is moved to the right to shift the rudder to the left, the fluid or liquid in the cylinder 114 is displaced through the pipe line 138 to the cylinder 28, and at the end of the stroke the valve 132 is opened to relieve pressure in the pipe line 134 to equalize the pressure in the system.

It has been found that because of expansion and contraction of the fluid or liquid in the system due to change in temperature, and also pulsations of the fluid in the system caused by vibrations or slight movements of the rudder, the steering arm 172 is infrequently off center. In instances where this occurs, upon movement of the steering wheel, as for example to the left, the piston 50 would be moved to the right. This movement of the piston 50 displaces the fluid in the cylinder 28 through the pipe line 138 to the cylinder 114. This cylinder, by reason of the off-center position of the steering arm 172 due to the vibrations of the rudder, is filled with fluid from the reservoir by-passed through the passage 68 in the head 54 of the piston 50 and conveyed by pipe line 138 to the cylinder 114. Hence, upon displacing fluid from the cylinder 28 to the cylinder 114 the quantity of fluid is in excess of the quantity necessary to effect the desired operation. This condition is overcome by a slight movement of the piston 140 to trip the valve 120, which permits the excess fluid to escape through valve 48, the pipe line 122, port 124 and pipe line 126 to the cylinder 26, thus equalizing the steering arms 102 and 172.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is:—

1. A steering apparatus comprising fluid pressure actuating means including opposed cylinders, a double end piston reciprocable in the cylinders, valves in the heads of the cylinders, manually operated means for moving the piston, means carried by the piston for controlling the valves, a fluid pressure actuated means including opposed cylinders, valves in the heads of the cylinders, a double end piston in the cylinders, means carried thereby for controlling the valves, a device operated by the piston, conduits connecting the cylinders of the fluid pressure actuating means to the corresponding cylinders of the fluid pressure actuated means, and conduits connecting the valves in the heads of the cylinders of the fluid pressure actuating means to the valves in the heads of the oppositely disposed cylinders of the fluid pressure actuated means.

2. A steering apparatus comprising a fluid pres-

sure actuating means including opposed cylinders having valves in their respective heads, a double end piston in the cylinders, manually operated means for moving the piston, reciprocable means carried by the piston for controlling the valves, a fluid pressure actuated means including opposed cylinders having valves in their respective heads, a double end piston reciprocable in the cylinders, means carried by the piston for controlling the valves, a mechanism operatively connected to the piston, conduits connecting the cylinders of the fluid pressure actuating means to the corresponding cylinders of the fluid pressure actuated means, and conduits connecting the valves in the heads of the respective cylinders of the fluid pressure actuating means to the valves in the oppositely disposed cylinders of the fluid actuated means.

3. In a steering apparatus the combination of a double end piston having an axial bore and a slotted portion, corresponding heads on the respective ends of the piston, the piston having passages therein back of the heads extending from the periphery of the piston to the axial bore, leak-proof cups on the heads having openings coextensive with the axial bore, plungers in the axial bore, stops on the adjacent ends of the plungers, extensions on the plungers protruding through the openings in the cups, and springs on the extensions retaining the cups on the heads of the piston.

4. In a steering apparatus the combination of a fluid reservoir, opposed cylinders communicating therewith, heads on the cylinders, relief valves in the heads, a double end piston in the cylinders having an axial bore and a cut-away portion, corresponding heads on the respective ends of the piston and passages in the piston back of the respective heads extending from the periphery of the piston to the axial bore providing communications between the cylinders to the reservoir, leak-proof cups on the piston heads having openings coextensive with the axial bore, plungers in the axial bore, stops on the adjacent ends of the plungers, extensions on the plungers protruding through the openings in the cups and

arranged for controlling the valves in the heads of the cylinders, means carried by the extensions for retaining the cups on the piston heads, means for actuating the pistons including a rotatable shaft extending through the reservoir, an arm on the shaft having a part extending between the stops on the adjacent ends of the plungers, and means for rotating the shaft.

5. A steering apparatus comprising a fluid pressure actuating device including opposed cylinders, a double-headed piston reciprocable in the cylinders, manually operative means for actuating the piston, valves in the heads of the cylinders, means carried by the piston for maintaining the valves in open position, a fluid pressure actuated device including opposed cylinders, a double-headed piston reciprocable in the cylinders, mechanism operated by the piston, valves in the heads of the cylinders, means carried by the piston for opening the valves, conduits connecting the cylinders of the actuating device to the corresponding cylinders of the actuated device, and conduits connecting the valves in the heads of the cylinders of the actuating device to the valves in the heads of the reversely arranged cylinders of the actuated device.

6. A steering apparatus comprising a fluid pressure actuating device including opposed cylinders, a double-headed piston reciprocable in the cylinders, manually operative means for actuating the piston, a fluid pressure actuated device including opposed cylinders, a double-headed piston reciprocable in the cylinders, means operated by the piston of the fluid actuated device, conduits connecting the cylinders of the actuating device to the corresponding cylinders of the actuated device, conduits connecting the cylinders of the actuating device to the oppositely disposed cylinders of the actuated device, valves controlling the last-mentioned conduits, and means carried by the respective pistons for controlling the valves whereby after a predetermined movement of the respective pistons the pressure in the actuating device, the actuated device, and conduits connecting these instrumentalities is equalized.

HERBERT C. BOWEN.
